(57) **CLAIM**

The ornamental design for a shadow frame, as shown and described.

DESCRIPTION

FIG. 1 is bottom view of a shadow frame.

FIG. 2 is a side view of the shadow frame, the opposite side being identical.

FIG. 3 is a top view of the shadow frame.

FIG. 4 is another side view of the shadow frame, the opposite side being identical.

FIG. 5 is an enlarged detail view of a portion of the shadow frame; and,

FIG. 6 is a cross sectional view of FIG. 1.

The broken line portion of FIG. 5 is included to show an unclaimed element and forms no part of the claimed design.
